UNITED STATES PATENT OFFICE.

EDWARD N. FRARY AND ERNEST A. FRARY, OF SOUTH DEERFIELD, MASSACHUSETTS.

ELECTRICAL SWITCH AND VALVE-CONTROLLING DEVICE

1,116,262.

Specification of Letters Patent.

Patented Nov. 3, 1914.

Application filed August 18, 1910, Serial No. 577,825. Renewed March 30, 1914. Serial No. 828,387.

To all whom it may concern:

Be it known that we, EDWARD N. FRARY and ERNEST A. FRARY, citizens of the United States of America, and residents of 5 South Deerfield, in the county of Franklin and State of Massachusetts, have invented certain new and useful Improvements in Electrical Switches and Valve-Controlling Devices, of which the following is a full, 10 clear, and exact description.

This invention relates in part to an improved switch or circuit closing device, and an object is to provide a switch of such character that when manually brought to 15 closed or circuit establishing position and the closing force is released, the switch will be immediately automatically moved to break, or leave open, the circuit.

A further object of the invention is to 20 provide a valve and combined therewith an electric switch, together with valve opening and closing means, which means is operative in its valve opening action to immediately establish an electric circuit and to then, 25 upon the release of the force manually applied, cause an opening of the switch to leave the circuit broken without imparting any degree of closing movement to the valve.

The special object for which the device 30 has been produced is to enable a person, such as an automobile driver, while sitting in the seat of the vehicle, to turn on the acetylene or other gas which leads to the burner of a lamp and simultaneously there- 35 with secure an ignition of the gas issuing from the burner of the lamp by reason of the establishment of the electric circuit in which a spark coil is usually employed, and with assurance that almost immediately the 40 gas is turned on and the gas lighted, the lighting circuit will, without requiring any thought or act on the part of the driver, be automatically opened to prevent the running down of the generator.

45 Other objects are to render the device very much simplified, compact, entirely practical and efficient.

The invention is described in conjunction with the accompanying drawings in which— 50 Figure 1 is a plan view of combined switches and valve controlling devices ap- purtenant to the gas supply pipes for sev- eral lamps of an automobile; Fig. 2 is a front elevation and partial section as taken

on line 2—2, Fig. 1; Fig. 3 is a cross sec- 55 tional view on line 3—3, Fig. 1; Fig. 4 is a plan view of the valve body and switch supporting portion of the device, indicat- ing by dotted lines the gas passages there- 60 within; Figs. 5, 6 and 7 are views showing in separated, partially engaged, and finally 65 engaged, relations parts comprising the valve and important portions of the switch and the handle for operating both the valve and the switch. Figs. 8 and 9 are face 70 views of the frictional tensioning spring ap- purtenant to the pluralized valves in dif- ferent positions assumed in its assemblage in relation to such valves. Fig. 10 is a dia- 75 gram indicating the connection of several valves and switches with gas pipes and gas lighting burners of the extreme front, in- 80 termediate and rear lights of an automobile.

Similar characters of reference indicate 75 corresponding parts in all of the views.

In the drawings,—A represents a metallic body having tapered holes or valve seating 85 sockets *a a* which extend from front to rear in parallel lines.

B represents a gas supply pipe which 80 leads into the body and connects with the horizontal passage 10 which intersects two of the valve receiving sockets, and by pas- 85 sage 12 connects with the third one of the valve seating sockets, and from the several valve seating sockets lead passages 13 with which are connected pipes C, C², and C³, which lead to the gas lighting burners dia- 90 grammatically indicated at *d*, *d*², and *d*³ of the front, intermediate and rear lamps D, 95 D² and D³ for an automobile. The courses of the passages 10, 12, and 13 in their rela- 100 tive planes, and in some cases one in front of another, are indicated by the dotted lines in both Figs. 2 and 4, and each plug valve E has a straight transverse way *e* there- 105 through so that, in a simple manner and as easily understood, the several valves close and open communication from the supply of gas in the tank G,—from which the sup- 110 ply pipe B leads with the several lamp burner supplying pipes C, C² and C³.

On the top of the valve body is a suitably thick layer *f* of insulating material, on which are contact pieces *g g g* which form electric 105 circuit terminals.

The valve body and the valves tightly seated and rotatably movable therein being

made of suitable metal, are utilized to form portions of electric conductors for the saving of considerable unnecessary wiring.

Each plug valve E is provided with an outwardly extending stem *h* having a quite short radially limiting stud *i* and also a fixed radially extending pin *j* which receives connection therewith of the retractile spiral spring *k* which will be hereinafter again referred to.

J represents a contact arm or member for co-action with the aforementioned contact piece *g* for each of the switches, the same comprising a collar portion *m* which loosely embraces the shank or stem of the valve and is positioned against the shoulder *n* at the place where the stem joins the plug like valve proper. The said collar portion of the contact arm *J* is provided with a right angular or hook shaped lug *o* which extends forwardly from the plane of movement of the contact arm.

L represents the operating handle for each switch, represented as having the ordinary form of a switch key and constructed with a tubular stem *q* which loosely embraces the valve stem and which is provided with a recess *s* which has a dimension greater than the diameter of the aforementioned limiting stud *i* which projects from the stem of the valve so that there may be in the circuit closing action a lost motion engagement between the operating handle and the valve.

The tubular shank of the key or operating handle *L* which is telescopically fitted about the stem of the valve has an outturned or radially extended lug *t* which is interengaged with the hook shaped lug *o* appurtenant to the contact arm *J*.

The aforementioned spiral spring *k* is connected for its retractile action by its one end to the contact arm and by its other end to the radial pin *j* of the valve stem.

The tubular shank *q* of the operating handle is recessed as indicated at *u* so that it may have its suitable freedom for lost motion relatively to the valve without obstruction by the radial pin *j* with which the spring connects.

The rear ends of the several plug valves E which protrude beyond the rear side of the valve body A are made with annular grooves *v*, and the flat spring M made of slightly undulating form and arranged alongside the back of the valve body has such an engagement with the grooved plug valve as to insure the seating thereof with an appropriate degree of frictional tension in the tapered sockets. The spring plate as shown is made with several holes *w* of a diameter as large as the full diameter of the rear extremity of each valve plug and with extensions *w*² of such holes so that by placing the plate with the larger portions of the recesses in registry with the valve ends, slip-

ping the plate to embracing relations with such valve ends and then sliding the plate endwise the spring is engaged both with the valves and in a degree of compression against the back of the valve body.

In the operation of opening one of the valves and closing the switch appurtenant thereto, a person will manually move the handle piece *L* from the position shown at the left of Figs. 1 and 2 to the position shown in the middle of said figures. This results firstly in the handle piece causing by its lug *t* a slight rotative movement with it of the contact arm, stretching and increasing the tension of the spring *k* before the recessed shank of the handle piece encounters the stud *i*, whereupon the handle piece, contact arm and valve are rotatively moved in unison to the position which causes the opening of the valve relatively to the gas passage for which is provided and the carrying of the end edge of the contact arm against the contact piece *g*; now the valve being opened and required so to remain, upon the release of the manual force applied to the handle piece the stretched spring *k* becomes effective to cause a withdrawal of the contact arm *J* from its bearing under and against the contact piece *g* as represented at the right hand portion of Figs. 1 and 2, thereby breaking the circuit which at the time of the opening of the valve has been closed. It will be stated at this time that the friction tight fitting of the valve in its socket insures such stability of the valve that it serves as the foundation or pulling point from which the retractile spring operates for its withdrawal from contact of the arm *j*.

By making the parts specifically as shown and described in conjunction with Figs. 5, 6 and 7, the plug valve and its stem, and the contact arm with its retractile spring may be made up and provided as a unit; and with these "units" fitted in the valve body which is inclosed in the casing Q having comparatively small circular holes in its front, the tubular shanks of the handle pieces may be inserted through such holes and have their projecting lugs brought to engagement with the lug provided contact arm, which, so far as the operation is concerned, is to all intents and purposes as a lever like member of the handle piece.

The wiring connections for the respective gas lighting circuits may be substantially the same as those described in our application for Letters Patent filed July 12, 1910, Serial No. 567,183, for an apparatus, the objects of which are similar to those of this invention, and over which this invention is deemed to have superiority by reason of its greater simplicity, compactness and cheapness. Therefore, it may be briefly mentioned that from the battery 20 and connected spark

coil 22 the wire 23 runs to connection at 24 with the metallic valve body A. This wire is, therefore, in metallic connection through the valve body and valves with the contact 5 arms J; and when the contact arms are against the contact pieces g circuits will be established by way of the wires 25, 26 and 27 to the gas lighting burners of the front, intermediate and rear lamps, the return current being understood as accomplished by 10 the wires 28 grounded in the metallic frame of the machine as also the wire 39 which completes the return to the battery. Therefore, the very simple device here illustrated 15 provides for the turning on of the gas in any of the three sets of lamps and establishment of the gas lighting current therefor.

We claim:

1. In a device of the character described, 20 in combination, a valve body, having a passageway therein, and forming part of an electrical circuit conductor, provided with a valve receiving socket therein, and having a contact member mounted thereon and insulated therefrom which constitutes a terminal 25 of an electric circuit in which said valve body is also comprised, a rotative valve plug in said socket controlling said passage way, a contact arm provided with a collar portion 30 embracing the shank of the valve plug, a spring applied for reaction between said contact arm and said valve plug, and an operating handle piece provided with a sleeve like shank telescopically fitting about and rotatable 35 relatively to the shank of the valve plug and having a projection which engages said contact arm, and having a lost motion engagement with the shank of the valve plug.
2. In a device of the character described, 40 in combination, a metallic passaged valve body having a contact piece insulated therefrom and having a plug valve rotatively fitted therein and provided with an outwardly extending stem provided with a radial 45 limiting stud and a radial pin, a contact arm having a collar portion loosely en-

circling the valve stem and provided with an offset lug, an operating handle piece provided with a tubular shank loosely telescopically fitted about the valve stem provided with a lug which engages the offset lug of the collar member of the contact arm, and having an opening the width of which is greater than that of said radial pin, and relatively to which such tubular shank has a lost motion engagement, and a spring applied for retractile action between said contact arm and said pin carried by the valve stem.

3. In a device of the character described, in combination, a metallic passaged valve body, having a contact piece mounted thereon and insulated therefrom and having a tapered socket for a plug valve extending therethrough from front to rear and intersecting the passage in said body, a plug-valve fitted through said socket, projecting at the rear of the body and having a forwardly extending stem provided with a limiting stud and a fixed radial pin, a spring located at the rear of the body and imparting a frictional seating tension to the plug-valve, a collar loosely encircling the valve-stem having a contact arm extended adjacent and for co-action with said contact piece and provided with a forwardly offset lug of hook shape, a spiral spring connected to and retractively operating between said contact arm and said radial pin, and an operating handle-piece made with a tubular stem, loosely embracing the valve-stem, provided with a recess having a dimension greater than the diameter of said limiting stud, for a lost motion engagement, and provided with an outwardly extending lug with which said hook-shaped lug appurtenant to the contact arm has an interengagement.

Signed by us at Springfield, Mass., in presence of two subscribing witnesses.
